UNITED STATES PATENT OFFICE

MARTIN M. KEENER, OF LANCASTER, PENNSYLVANIA

FOLDING PIN TICKET

Application filed March 28, 1931. Serial No. 526,069.

This invention relates to an improvement in folding pin tickets.

The object of the invention is to provide a folding pin ticket for use in marking prices, etc. on merchandise offered for sale in retail stores or the like, and which ticket will be of an improved form and an improvement over the folding pin tickets which have heretofore been used.

An advantage of this folding pin ticket is that it is not necessary for a person who is applying the ticket to the fabrics to touch the sharp ends of the wire at any time, before, during, or after attaching the ticket to the fabrics. Therefore, the application of the tickets does not cause infection or blood poisoning which often results from pricks of the fingers by the points of the wire, and as a result there is no retardation in the speed of applying these pin tickets to the fabrics. On the contrary, there is a substantial increase in the number of these pin tickets which can be applied in a given length of time over the number of pin tickets heretofore in use.

A further advantage is in the less number of operations required for attaching the pin tickets to the fabric. The flap end which protects the points of the folding pin ticket heretofore in use is omitted in this invention, as there are no points to protect. Less material is used in the construction of this pin ticket, which leads to an economical product at a reduced cost.

In the accompanying drawing:

Fig. 1 is a perspective view of the folding pin ticket open and before attachment;

Fig. 2 is a similar view of the opposite side of the pin ticket, in the course of attaching to the fabric;

Fig. 3 is a longitudinal sectional view of the ticket after attachment;

Fig. 4 is a transverse sectional view showing the ticket in end elevation;

Fig. 5 is a perspective view of the attached ticket in its final form; and

Fig. 6 is an end elevation of the ticket, the fabric being in section with the bails bent down.

The sides 1 and 2 of the ticket may be

constructed from tag stock that folds without breaking, and a fold is formed as at 3 to join the ticket sides 1 and 2 together.

The ticket side 1 is provided with holes 4 therethrough near its outer edge, through which a wire form, designated generally by the numeral 5, extends, which form is constructed of small pin wire or the like and is bent to form a handle 6. The wire form 5 is bent laterally as at 7 at the inner ends of the handle 6 and extends through the holes 4 to form bails 8. The sides of the handle 6, the bails 8 and the prongs 9 extend in two parallel planes arranged longitudinally of the ticket side 1. The ticket side 2 is provided with slots 10 therein, through which the bails 8 extend, as shown in Fig. 3. Mere slits in the ticket side 2 may be sufficient for passage of the bails therethrough.

A strip of fabric is designated F in Figs. 2 to 6, which show the application of the folding pin ticket thereto. A person, in applying the folding pin ticket to the fabric F, holds the handle 6 with the thumb and fingers of one hand, and with the ticket side 2 on the underside of the fabric, the prongs 9 are pushed through the fabric at the proper position, after which the wire form 5 is swung to a position generally at right angles to that shown in Fig. 2, the form swinging 80 on a fulcrum formed by the holes 4, after which the ticket side 2 is brought toward the side 1, and the slots 10 are forced over the bails 8, as shown in Figs. 3 and 4, after which these bails 8 are bent down against the outer face of the side 2, as shown in Figs. 5 and 6, which locks the ticket to the fabric and holds the same thereon while at the same time protecting the prongs 9 of the wire form.

Both the construction of the ticket and its application are extremely simple, which simplifies the manner of attaching without endangering the fingers of a person applying the same, because it is not necessary to touch the prongs in order to apply the ticket to the fabric.

I claim:

1. A pin ticket of the character described comprising a ticket side, a wire form hingedly connected with the ticket side and having 100

portions to engage a fabric to hold the same in place, and a handle connected with the wire form and at the opposite end thereof from the fabric engaging portions to manipulate the form.

5 2. A folding ticket of the character described comprising ticket sides, one of said sides having one or more holes therein, a wire form fulcrumed in the holes and having 70 means for engaging and holding a fabric to the ticket, and a handle connected with the form and at the opposite end thereof from the fabric engaging means for swinging the form in the holes.

15 3. A pin ticket of the character described comprising ticket sides connected together, one of the sides having a plurality of holes therein, a wire form having angular portions extending through the holes and forming 75 fulcrums for the form, a handle connected with the form to swing the same on its fulcrums, and means on the opposite side of the fulcrums from the handle for engaging and holding the fabric in the ticket.

25 4. A pin ticket of the character described comprising ticket sides connected together, one of the sides having a plurality of holes therein, a wire form having angular portions extending through the holes and forming 80 fulcrums for the form, a handle connected with the form to swing the same on its fulcrums, means for engaging and holding the fabric in the ticket, the other side having 85 slots formed therein, and bails connected 90 with the wire form and adapted to extend through the slots to hold the sides together.

40 5. A pin ticket of the character described comprising ticket sides connected together, one of said sides having holes in an end portion 95 thereof, a wire form having a handle member formed with approximately parallel side portions and arranged on one side of the ticket side, said side portions terminating in angularly bent portions extending 100 through the holes and forming fulcrums for the wire form to permit swinging thereof in the holes, and prongs connected with the angularly bent portions to engage and hold a fabric in the ticket.

45 6. A pin ticket of the character described comprising ticket sides connected together, one of the sides having spaced holes in an end portion thereof, a wire form having a handle member, said handle member having approximately 105 parallel sides terminating at their rear ends in angularly bent portions forming bails, said angular portions extending through the holes and forming hinged supports for the wire form in the holes, the other side of the ticket having slots formed therein to receive the bails to hold the sides together.

50 7. A pin ticket of the character described comprising ticket sides connected together, one of the sides having spaced holes in an 110

end portion thereof, a wire form having a handle member, said handle member having approximately parallel sides terminating at their rear ends in angularly bent portions forming bails, said angular portions extending through the holes and forming hinged supports for the wire form in the holes, the other side of the ticket having slots formed therein to receive the bails to hold the sides together, said bails terminating in prongs to engage a fabric, the prongs, bails and sides of the handle being disposed approximately in two parallel planes extending longitudinally of the ticket.

15 8. A pin ticket of the character described comprising ticket sides connected together, a wire form hingedly connected with one of the sides, and having a bail connected therewith, and a prong for engaging a fabric or the like, the other side having a slot formed therein for receiving the bail to hold the sides together.

20 9. A pin ticket of the character described comprising ticket sides connected together, a wire form hingedly connected with one of the sides for swinging movement relative thereto and having spaced and approximately parallel bails connected therewith, the other side having slots therein to receive the bails, said bails being bent laterally on the outer side of 95 the last-mentioned ticket side to hold the sides together.

25 10. A pin ticket of the character described comprising ticket sides connected together, one of the sides having holes therein, a wire 100 form having portions thereof extending through the holes and hingedly connected with the side in the holes, approximately parallel bails extending outwardly from the face of said ticket side and terminating in 105 prongs, the other side having slots formed therein through which the bails extend, said bails being bent laterally on the outer face of the last-mentioned side to hold the sides together.

30 11. The combination with a sheet of material having slots formed therein, of fastening means on a side of said sheet of material and having two sides, each side having a laterally bent bail arranged to be inserted 115 through the slots formed in the sheet of material, and thereafter bent down on the opposite side of the sheet of material from the main portion of the fastening means.

35 12. The combination with a pin-ticket having slits therein, of fastening means made of wire bent into U-shape to form two sides, said sides being bent to form U-shaped bails intermediate of the ends of the sides and adapted 120 to be inserted through the slits in the ticket, and bent laterally thereof.

40 13. The combination with a pin ticket having approximately parallel slits therein, of a fastening device comprising sides having parallel bails in position to project through 125

the slits and adapted to be bent laterally thereof to prevent removal from the slits.

14. The combination with a pin ticket having a slit therein, of a fastening device having 5 the main portion thereof on one side of the ticket, said main portion having a bail arranged to project through the slit and be bent laterally thereof to prevent removal from the slit.

10 15. The combination with a pin ticket having a slit therein, of a wire form disposed on one side of the ticket, said form having a bail formed therein and beginning and terminating on said side of the ticket and 15 arranged to project through the slit and be bent laterally thereof to prevent removal from the slit.

16. A device of the character described comprising a ticket, and an approximately 20 U-shaped form having approximately parallel side members joined together at one end of the form, said side members having laterally bent portions intermediate their ends and extending through the ticket hingedly 25 connecting the form thereto, said side members terminating in prongs at the opposite end of the form from the first-mentioned joined end.

17. The combination with a ticket, of an 30 approximately U-shaped wire form having a handle portion arranged on one side of said ticket, a pair of side members extending continuously in the same general direction from said handle portion, each side member having a laterally bent portion intermediate its ends and movably passing through the ticket and extending along the opposite side thereof and terminating in a prong.

18. The combination with a ticket, of a 40 wire form having a portion projecting through the ticket adjacent an end thereof, and forming a fulcrum for the form, one end portion of the form on the inner side of the fulcrum having one or more fabric engaging 45 prongs, and the opposite end portion of the form projecting outwardly beyond the end of the ticket and providing a handle for manipulating the ticket.

50 In testimony whereof I affix my signature.

MARTIN M. KEENER.
